DRAFT KEY RETAINER

Emil H. Blattner, Buffalo, N. Y., assignor to The Symington-Gould Corporation, Depew, N. Y., a corporation of Maryland

Application July 8, 1949, Serial No. 103,675

3 Claims. (Cl. 85—8.1)

1

This invention relates to a draft key retainer and more particularly to a type thereof which is designed to be locked positively in position.

A primary object of the invention is the provision of a positive lock in a draft key retainer to thereby prevent its accidental or unwarranted loss or removal during service.

Another object of the invention is the provision of increased bearing areas in a draft key retainer so that appreciable bearing surfaces or areas will be presented to other components and thereby materially project the serviceability of the retainer.

Still another object of the invention is to provide an improved draft key retainer which can execute only a very limited rotary motion and thereby prevent extremities of a head portion thereof from contacting associated structure, which if caused to exist would impart a lifting action to the retainer and further cause damage to or failure of the retainer.

A further object of the invention is to provide an improved draft key retainer which is of relatively light weight, positive in action, easily manufactured and inexpensive when compared with analogous structures of the prior art and in accepted usage.

The above and numerous other objects of the invention will become apparent from the succeeding description when considered together with the accompanying drawing, wherein:

Figure 1 is a plan view of an embodiment of the invention shown associated in operable position with a portion of a draft key.

Figure 2 is an elevational view taken along the lines 2—2 of Figure 1, looking in the direction of the arrows.

Figure 3 is a side elevational view taken along the lines 3—3 of Figure 2, looking in the direction of the arrows.

Referring now in detail to the drawing, wherein like reference characters designate like parts, the numeral 1 is employed to indicate, in a somewhat general manner, an arrangement exemplifying a form of the present invention. The arrangement includes a draft key 2 only a portion of which is illustrated because it, in and of itself, forms no part of the present invention. It may, however, be well to set out herein, for the complete understanding of the invention, that the draft key is primarily employed in railway vehicles and is arranged to extend transversely through a center sill construction (not shown) to function as a force transmitting medium from a related part of a draft rigging (not shown) to the center sill construction. This draft key can be, if desired, arranged to travel in a slot 3 of

a cheek plate 4 for a predetermined distance depending entirely upon the prearranged or permitted compressive travel of a draft gear. The draft key is formed on one end thereof (not shown) with an integral head which prevents displacement of the draft key in one direction only. In order that the draft key may be assembled with related parts thereof to assist in forming a draft arrangement, a free end 5a thereof presents no obstructions and therefore it is necessary to associate some device with this otherwise free end so that the draft key may at all times, be retained in operable position.

Toward the accomplishment of this last named feature, the device hereinabove referred to, takes the form of a removable draft key retainer and it is this last named component that has been herein improved over the many devices of an analogous nature to be found in the prior art. The draft key retainer as improved herein is designated by the general reference character 5 and comprises a shank 6 and a head 7, the latter of which crosses the shank at right angles thereto and is formed so as to be an integral part at one or an upper end thereof. A forging lends itself admirably well to this retainer design or configuration. The shank 6 has an intermediate portion 8 thereof formed as a substantially true cylinder so as to fit into a suitably arranged aperture 9 in the draft key. By this arrangement the retainer is arranged, within certain predetermined limits, to pivot about its center in response to service forces to which it will be subjected. As will be understood the draft key fits in the center construction rather loosely and therefore is arranged to move or be moved transversely of the center sills as well as execute movements which will dispose the draft key at an oblique angle to the center sills or what is commonly termed the longitudinal center line of the car (not shown). Because of these possible movements the draft key retainer should be arranged to pivot about its vertical axis but only within predetermined limits for otherwise, if the key assumes a position whereby the head 7 thereof is directed transversely of the car as opposed to longitudinally of the car as illustrated, the head then will be in a position where the boss 4a of the cheek plate 4 will foul the retainer head or exert a lifting action on the retainer to shear the holding means thereof and result in the loss or accidental displacement of the retainer. Also if the entire shank of the retainer is made to conform to a substantially cylindrical body or member throughout its length or height then only a line contact will be presented between the cheek plate boss and retainer shank. In order to

present an appreciable bearing area between the retainer and cheek plate, the shank, above and below the intermediate or central portion, has formed on what may be termed the inside or in-board side thereof, flat or plain surfaces or faces 10. These surfaces are inset or set back with respect to the substantially cylindrical portion and therefore are arranged to not only present adequate clearance between the retainer and cheek plate boss to afford ample maneuverability of the draft key during service but also present adequate wearing or bearing surfaces on the retainer for engagement with the cheek plate boss. Another distinct advantage gained by this so far described construction or association is that the present draft key retainers approved as a standard for all American railroads by the Association of American Railroads, may be altered to gain all the advantages flowing from the present structure. The retainer head is also provided with a flat or plain inboard face 11 which is in vertical alignment with the faces 10 to thereby permit the faces 10 to function as intended and also increase the bearing or guiding area between the retainer and cheek plate boss.

Many devices have been heretofore suggested in order to maintain the retainer in an operable position, the most simple expedient being the insertion of an ordinary cotter pin (not shown) in an opening 12 formed transversely of the shank at a location at an end opposed to the one occupied by the head 7. This practice, while in general usage, is extremely impractical because of the shearing effects on the cotter during service and the ultimate complete shearing of the cotter pin and subsequent detrimental loss or displacement of the retainer. The device herein proposed and believed far superior to the use of the ordinary cotter pin is characterized by a locking pin 13 which may, as desired, be formed of commercial cylindrical rod material having a circular cross-section but it will be understood that this invention is not to be so minutely or necessarily limited. An axial bore 14 is drilled or otherwise formed in the shank to extend partly thereto and completely through the head. This bore is of a size or diameter so as to neatly accommodate a terminal leg 15 of the locking pin which is housed in the bore. Communicating with the axial bore is an open kerf or trough-shaped recess 16 extending transversely of the head and arranged to accommodate a horizontally directed arm 17 of the locking pin which is cradled in the recess. While not absolutely necessary for the successful carrying out of the teachings of the present invention but merely as a precautionary measure, welds 18 are deposited in the recess to further bind or secure the locking pin to the head and prevent absolutely its separation therefrom.

The arm of the locking pin is extended outwardly or horizontally from the retainer head in a direction away from the cheek plate or center sill until it reaches a point beyond the adjacent limit or the previously mentioned free end of the draft key as clearly indicated in the drawing. The pin arm then merges into a downwardly or vertically directed intermediate or connecting stem 19 which passes through the extended horizontal plane of the draft key so as to project above and below the vertical extent of the draft key. The lower or what might at this puncture be termed the free end of the connecting stem, merges into an angularly directed or reentrant finger 20 which is directed

back toward the center sill and appearing at a location, at one time, directly below the related end of the draft key and at all times below the horizontal extended plane of the draft key. Normally, before complete assembly with the draft key, the connecting stem and reentrant finger are disposed at a position as indicated in Figure 2 particularly by the diagrammatic lines 19a and 20a and are spaced an appreciable distance from the related end of the draft key. This pre-arranged position of the stem and finger will permit the introduction of the shank into the aperture 9 after which hammer blows at the junction of the stem and finger will force the finger particularly, inwardly toward the shank to underlie the draft key and prevent accidental displacement of the retainer.

From the above it will be noted that various changes and alterations may be made to the illustrated and described specie of the invention without departing from the spirit of the invention and scope of the appended claims.

I claim:

1. In a draft key retainer, the combination of, a body portion comprising a shank having a crosshead at one end thereof, an intermediate portion of said shank being substantially round to fit into an aperture of said draft key, and areas of said shank at each end of said intermediate portion and including said crosshead presenting flat coplanar surfaces inset from said intermediate portion and disposed parallel to the axis of said retainer.

2. In a draft key retainer, the combination of, a body portion comprising a shank having a crosshead at one end thereof, an intermediate portion of said shank being substantially round to fit into an aperture of said draft key, areas of said shank at each end of said intermediate portion and including said crosshead presenting spaced flat coplanar surfaces inset from said intermediate portion disposed parallel to the axis of said retainer, and locking means connected to said retainer for securing said retainer to said draft key.

3. In a draft key retainer, the combination of, a body portion comprising a shank having a crosshead at one end thereof, an intermediate portion of said shank being substantially round to fit into an aperture of said draft key, areas of said shank at each end of said intermediate portion and including said crosshead presenting flat coplanar surfaces inset from said intermediate portion and disposed parallel to the axis of said retainer, a locking pin secured to said retainer, and a bendable portion of said pin outstanding from said head and arranged to be urged toward said shank to underlie said draft key for preventing separation of said draft key and retainer.

EMIL H. BLATTNER.
